UNITED STATES PATENT OFFICE.

CLARA HELENE RASMUSSEN, OF OSHKOSH, WISCONSIN, ASSIGNOR OF ONE-FOURTH TO
WM. C. KARGUS AND ONE-FOURTH TO GEO. A. KNAAK, OF OSHKOSH, WISCONSIN.

HAT-FASTENER.

953,156.

Specification of Letters Patent. Patented Mar. 29, 1910.

Application filed October 10, 1908. Serial No. 457,164.

To all whom it may concern:

Be it known that I, CLARA HELENE RASMUSSEN, a citizen of the United States, residing at Oshkosh, in the county of Winnebago and State of Wisconsin, have invented a new and useful Hat-Fastener, of which the following is a specification.

This invention relates generally to hat fasteners, and particularly to that class 10 adapted for permanent connection with women's hats.

The object of the invention is in a ready, simple, thoroughly feasible and practical manner, to secure a woman's hat irrespective of the character of the material of which it is made, that is to say, whether it be stiff or soft, in position in such manner as positively to prevent its accidental removal; to obviate the liability of the hair of 20 the wearer catching upon the fastener when the hat is being removed; and to provide a neat, efficient and durable hat fastener, which may be secured to a hat in such manner as practically to be invisible.

25 With the above and other objects in view, as will appear as the nature of the invention is better understood, the same consists, generally stated, in the novel construction and combination of parts of a hat fastener, 30 as will be hereinafter fully described and claimed.

In the accompanying drawings forming a part of this specification, and in which like characters of reference indicate corresponding parts:—Figure 1 is a view in perspective of a hat fastener constructed in accordance with the present invention. Fig. 2 is a horizontal sectional view through a portion of the band of the fastener, displaying the 35 means by which it may be held at the desired circumferential adjustment. Fig. 3 is a perspective detail view, on an enlarged scale, of a portion of the fastener. Fig. 4 is a section on the line A—B of Fig. 3.

40 The fastener comprises a band 1 constructed of a length of sheet metal, preferably of brass, and which is provided at intervals in its length with out struck prongs 2 that are designed to pierce the inside band, 45 lining or material partly, the tension of the band together with the prongs 2 serving to hold the band firmly in position.

In order to render the band adjustable, so 50 as to adapt it to fit hats of different sizes, 55 one end of the band is provided with any

number of out struck seats 3, any one of which is designed to be engaged by an out struck teat 4 carried by the other end of the band, but in order to hold the two terminals of the band assembled, that one having the 60 seats formed in it, is provided with two opposed flanges 5, which may be integral with the band or be secured thereto, and between which the other end of the band is adapted to slide, as clearly shown in Fig. 2. 65

In order to retain the teat in the appropriate seat, after the required adjustment has been secured, a key or locking member 6 is provided which fits between the flanges and the terminals of the band therein, and 70 thus locks the teat in the seat. This key is provided with an orifice 7, one wall of which is straight and is provided to enable the key to be removed when desired.

Projecting through one edge of the band 75 are two spaced guides 8, each of which is provided with a longitudinal slot 9. These guides are engaged by slides 10, which are constructed of metal and are approximately U-shaped in cross section. Each of these 80 slides is provided with four legs 11, two being arranged on each side of the band, and with a fifth leg or tongue 12, that is designed to project through the slot 9, and thus hold the slides assembled with the 85 band.

The legs are provided with orifices 13 that register with the slots 9, and these orifices are engaged by two-pronged pins 14, the shanks of which preferably flare outward, 90 in order to take a firm hold upon the hair. The bends 15 of the pins may be constructed as shown or otherwise, and may have ornamental heads connected with them or not, as preferred. 95

By having the slides arranged for longitudinal movement upon the guides, the pins may be adjusted so as to be best adapted to meet the prevailing styles in which the hair is worn, that is to say, the pins may be 100 arranged at the back of the head, or on each side opposite the temples, and as the pins cross each other, it will be seen that the assemblage of the pins and the hair will be of a most stable character. 105

In positioning the fastener upon a hat, the key 6 is removed, and the band adjusted to the proper size to fit against the inner surface of the side crown of a hat, and after the prongs have pierced the inside 110

band or lining, the key 6 will be positioned, thus to lock the terminals of the band together. The slides are then adjusted upon the guides to the proper points. When the 5 band is attached to a hat so as to extend around the interior of the crown of the hat the adjustment of the slides on the band becomes substantially circumferential and the adjustment of the pins in the slides becomes substantially radial with relation to 10 the band. When the hat is to be placed upon the head, the pins are nearly withdrawn, entire removal being prevented by flattening or enlarging their points, and 15 after the hat is properly arranged they are forced inward, and thus secure the hat in position.

The guides will project slightly below the under brim of the hat but will not be exposed to view, as they will be hidden by the 20 hair of the wearer, or by the trimming of the hat.

It is to be understood that the orifices 13 in the slides are to be of such size as to permit of the pins having the requisite play 25 or rocking motion, to allow the user to position them in the most comfortable and efficient manner.

The improvements herein described while 30 simple in character, will be found thoroughly efficient for the purpose designed and will result in the presentation of a cheap, practical and useful article for women's use.

35 I claim:—

1. A hat fastener comprising an attaching band having its ends brought together, slides carried by the band and adjustable circumferentially with relation thereto, and pins 40 carried by the slides and mounted therein for adjustment radial to the band.

2. A hat fastener comprising an attaching band having a plurality of guides in separated relation, a slide for each guide mounted 45 on the band for adjustment therewith and pins carried by the slide and adjustable therethrough in a direction substantially radial to the band.

3. A hat fastener comprising an attaching 50 band provided with a plurality of guides and having its ends brought together, a slide for each guide and mounted on the band and adjustable circumferentially with relation to the band, and pins carried by the 55 slides and adjustable therethrough in a direction substantially radial to the band.

4. A hat fastener comprising an adjustable attaching band provided with a plu-

rality of segmental guides, slides mounted for longitudinal movement within the 60 guides, and longitudinally adjustable pins carried by the slides.

5. A hat fastener comprising a band provided with attaching prongs and having its ends brought together, means for securing 65 the ends of the band in locked relation and for permitting the adjustment of the band as to its circumferential extent and there holding it, pins carried by the band, and means for supporting the pins on the band, 70 said means being adjustable along the band in the direction of its circumference and also carrying the pins for adjustment of the latter in a direction substantially radial to the band.

6. A hat fastener comprising a band provided with means to attach it to a hat, a plurality of longitudinally slotted guides extending from one edge of the band, slides mounted on the guides and provided with 80 tongues extending through the slots in said guides, and pins projecting through the slides and the slots of the guides.

7. A hat fastener comprising a band provided with means to attach it to a hat, a plurality of longitudinally slotted guides extending from one edge of the band, slides straddling the guides and provided with 85 orifices registering with the slots of the guides, and pins projecting through the 90 slots and the orifices.

8. A hat fastener comprising a band provided with means to attach it to a hat, a plurality of longitudinally slotted guides extending from one edge of the band, slides 95 straddling the guides, and provided with orifices registering with the slots of the guides, and with tongues projecting through the slots to hold the slides assembled with the guides, and pins projecting through the 100 slots and orifices.

9. A hat fastener comprising a band provided with means to attach it to a hat, and having one end provided with opposed flanges and with seats, and its other end 105 slidably mounted between the flanges and provided with a teat to engage the seats, a key engaging the flanges to hold the teat in a seat.

In testimony that I claim the foregoing 110 as my own, I have hereto affixed my signature in the presence of two witnesses.

CLARA HELENE RASMUSSEN.
